FISHING ROD HANDLE GRIP

Terry J. Kirk, 157 N. Bellevue,
Memphis, Tenn. 38104

Filed Jan. 9, 1967, Ser. No. 5,344

Term of patent 14 years

(Cl. D22—23)

FIG. 1

FIG. 2

FIG. 3

FIG. 4

FIG. 5

FIG. 1 is a side elevational view of a fishing rod handle grip, showing my new design.

FIG. 2 is a bottom view thereof.

FIG. 3 is a top view thereof.

FIG. 4 is a side elevational view thereof as viewed from the opposite side from that shown in FIG. 1.

FIG. 5 is an end view thereof.

The broken lines are shown for illustrative purposes only.

I claim:

The ornamental design for a fishing rod handle grip, as shown and described.
